WALTER S. MINGIS, OF NEW YORK, N. Y.

Design No. 4,436, dated October 25, 1870

DESIGN FOR A HEAD-BAND.

The Schedule referred to in these Letters Patent and making part of the same

To all whom it may concern:

Be it known that I, WALTER S. MINGIS, of the city of New York, in the county and State of New York, have invented a new and original Design for Head-Band; and I do hereby declare that the following is a full, clear, and exact description thereof, which will enable others skilled in the art to make and use the same, reference being had to the accompanying photographic illustration forming part of this specification.

The nature of my invention is fully represented in the accompanying photographic illustration, to which reference is made.

I claim as my invention—

The design for a head-band, as shown.

W. S. MINGIS.
